Inventor:

Elizabeth Eunice Merrill

UNITED STATES PATENT OFFICE.

ELIZABETH EUNICE MERRILL, OF LOS ANGELES, CALIFORNIA.

DESIGN FOR A NURSE-DOLL.

50,477.

Specification for Design.

Patented Mar. 20, 1917.

Application filed January 25, 1917. Serial No. 144,544. Term of patent 3½ years.

To all whom it may concern:

Be it known that I, ELIZABETH EUNICE MERRILL, a citizen of the United States, residing in the city of Los Angeles, in the county of Los Angeles and State of California, have invented a new, original, and ornamental Design for a Nurse-Doll, of which the following is a specification, reference being had to the accompanying drawing, forming part thereof.

In said drawing:

Figure 1 is a front elevation of a nurse doll showing my design.

Fig. 2 is a rear view of a nurse doll showing my design.

I claim—

The ornamental design for a nurse doll as shown.

ELIZABETH EUNICE MERRILL.
